UNITED STATES PATENT OFFICE.

BENJAMIN VALLERY, OF COLFAX, LOUISIANA.

CRATE FOR SYRUP-CANS.

1,359,451.

Specification of Letters Patent. Patented Nov. 16, 1920.

Application filed May 27, 1920. Serial No. 384,697.

To all whom it may concern:

Be it known that I, BENJAMIN VALLERY, a citizen of the United States, residing at Colfax, in the parish of Grant and State of Louisiana, have invented certain new and useful Improvements in Crates for Syrup-Cans; and I do hereby declare the following to be a full, clear, and exact description of the invention, such as will enable others skilled in the art to which it appertains to make and use the same.

The present invention relates to improvements in crates, more particularly for holding syrup cans, and has for an object to provide a strong and durable crate of inexpensive structure which is adapted for ready application to and removal from the cans.

In accordance with the present practice the cans are required to be sealed to avoid spilling of the contents during shipment, and even taking this precaution syrup is constantly being lost through spilling and the cans are apt to become dented and staved in from the hard usage to which they are subjected. The invention eliminates these difficulties and avoids the necessity for sealing the cans.

In the accompanying drawings forming a part of this application, and in which similar reference symbols indicate corresponding parts in the several views:

Figure 1 is an end view of a crate constructed in accordance with the present invention.

Fig. 2 is a sectional view taken on the line 2-2 in Fig. 1.

Fig. 3 is a transverse sectional view taken on the line 3-3 in Fig. 2.

Fig. 4 is a perspective view of one of the crate heads; and

Fig. 5 is a perspective view of one of the coupling rods.

Referring more particularly to the drawings, the improved crate is composed of a pair of heads 1 and 2 of a substantially triangular form with the corners rounded off, and preferably being reinforced with cleats 3 and 4 attached by screws 5 and 6 or other fastenings. The cleats 3 and 4 are particularly of advantage where the heads 1 and 2 are made out of more than one piece. Both the heads and the cleats are generally made of wood, although other material may serve the purpose equally well.

In the heads are bored, or otherwise produced, a central and a number of side holes

7 and 8 to receive coupling rods by which the heads 1 and 2 are clamped against the opposite ends of the syrup cans indicated at 9 in dotted lines. The cans held by each 60 crate are preferably three in number, as indicated in Figs. 1 and 3, they being arranged in the triangular relation shown.

Angle pieces 10 are secured as by screws or other fastenings to the inside faces of the 65 heads 1 and 2, and are spaced sufficiently far apart to receive the sides of the cans 9. The angle pieces 10 are preferably so assembled on the heads that two of such pieces are engaged by each can, and the pieces 10 thus 70 mounted in pairs act to confine the cans on the heads and prevent their movement in a lateral direction.

The tie rods employed are preferably composed of a pair of bolts 11 and 12 having 75 threaded ends 13 and 14 adapted to receive nuts 15 and 16. The center tie rod also preferably is provided with washers 17 and 18 adapted to take against the outside faces of the heads 1 and 2, as shown 80 plainly in Fig. 2. The bolts 11 and 12 are provided at their inner ends with hooks 19 and 20 adapted to engage one another in order to couple the bolts together in a flexible manner. The holes 8 in the heads are 85 preferably reinforced with metal strips 21 secured as by screws or other fastening means 22, and having perforations in alignment with the holes 8. The nuts on the side tie rods directly engage the strips 21 without the necessity of employing the washers 17 and 18.

In use the two heads 1 and 2 are clamped against opposite ends of the three syrup cans 9 which engage the angle pieces 10. 95 The nuts 15 and 16 are thereupon threaded on the tie rods and the cans are effectively held in the crate thus formed without any likelihood of leakage and without danger of injury to their contents during transportation. The center tie rod passes in the spaces between the three cans and the hooks 19 and 20 engage the side of the cans, as shown in Fig. 3, thus assisting to center the same.

100 It is obvious that those skilled in the art may vary the details of construction and arrangements of parts without departing from the spirit of my invention, and therefore I do not wish to be limited to such 110 features except as may be required by the claims.

I claim:

1. A crate for syrup cans comprising a pair of heads arranged in triangular formation adapted to receive a plurality of syrup cans also arranged in substantially triangular formation, coupling means secured to the central portions of said heads and passing through the space between said syrup cans, and other coupling means also engaged with said heads at or near the angles thereof and extending outwardly of the exposed portions of said syrup cans, substantially as described.
2. A crate for syrup cans comprising a pair of heads adapted to be fitted against the ends of the cans, tie rods coupled to said heads, said tie rods composed of bolts having flexible interengaged hooks at their adjacent ends, substantially as described.
3. A crate for syrup cans including a pair of heads of substantially triangular form adapted to be fitted against the ends of a plurality of syrup cans placed in substantially triangular arrangement, a flexible tie rod passing from one head to the other and engaging with the central portions

thereof, said flexible tie rod passing through the space between the cans and having means for engaging such cans, and other flexible tie rods engaged between the heads 30 and lying outwardly of the exposed portions of the cans, substantially as described.

4. A crate for syrup cans including a pair of heads adapted to be fitted against the ends of the cans, and tie rods coupled 35 to said heads, said tie rods having flexible joints therein, substantially as described.

5. A crate for syrup cans including a pair of heads of substantially triangular form with rounded edges having holes 40 therein, means for reinforcing the heads, angle pieces on the inner faces of the heads adapted to engage against the edges of the cans, tie rods passing through the holes in the heads for connecting the plates together, 45 said tie rods composed of bolts having flexible interengaged hooks at their adjacent ends, and means on the outer ends of the tie rods engaging the outer faces of the heads to hold the tie rods and heads coupled together, substantially as described.

BENJAMIN VALLERY.
